UNITED STATES PATENT OFFICE

2,618,883

DUST GUN

Albert Morsink, Enschede, Netherlands

Application February 15, 1949, Serial No. 76,599
In the Netherlands February 16, 1948

2 Claims. (Cl. 43—146)

1

The invention relates to a dust-gun for dispensing powders such as insecticides with a perforated upperwall in which a bag is fixed in telescopic moving cylinders, characterized by the fact, that the bag is airtightly fixed by its upper edge to the upper edge of the telescoped cylinder, and filling up nearly the whole contents of the same cylinder, the bag being closed at the other end and being so shorter than the telescoped cylinder which is formed with an open bottom. Both cylinders fit exactly in respect to in each other and the telescoping lower or movable cylinder is provided in the bottom thereof with a back-valve acting means.

According to another object of the invention the bottom of the movable cylinder (the lower) is loosely supported by an inwardly directed edge of the cylindrical wall, so that the bottom is lifted when the said cylinder is moved downwardly with respect to the rigid, telescoped cylinder and so that air may enter the space below the bag.

Further objects, advantages and capabilities of the invention will appear from the following description of two embodiments thereof in conjunction with the accompanying drawing, in which

Fig. 1 is a sectional view through the improved dust gun,

Fig. 2 is a similar view of another form of the bottom of the movable or telescoping cylinder, and

Fig. 3 is a plan view of this bottom.

In Fig. 1 the rigid cylinder is indicated by 2. 1 is the outer or movable cylinder, 3 is the bag, to be filled with powder. The bag 3, when closed, is shorter than the inner, telescoped cylinder 2, and fixed airtightly at 4 to the upper inner edge of the cylinder 2. This cylinder 2 is open at its lower end and closed at its upper end by a perforated lid 5.

The bottom 6 of the movable or telescoping cylinder lies loosely upon the inwardly directly edge 7. When the dust-gun is out of use the cylinder 2 is capped by the cylindrical lid 8.

When the bag 3 is filled with powder from the lower end 9, this end is closed and it will be noted that the end of this bag does not extend beyond the lower edge of the rigid cylinder 2 and therefor the bottom 6 of the other cylinder will never come into contact with the bag.

To dispense the powder the movable cylinder 1 is quickly pressed inwardly over the rigid cylinder 2, and, because the bag fits nearly exactly in the cylinder 2, the air in the space between

5 the bottom 6 of the cylinder 1 and the bottom surface 9 of the bag is compressed and presses the powder to the outside. The side walls and bottom of the bag are, of course, air impervious to permit such compression. Further, the exact fit of the bag in the cylinder facilitates such compression since the cross-sectional area of the bag, substantially throughout its length, is substantially equal to the cross-section of the inner cylinder 2 thereby substantially or largely confining the compressed air to the bottom surface 9.

Then the movable cylinder 1 is moved back and the air is sucked along the opening bottom 6 because the air pressure will open the said bottom.

In Figs. 2 and 3 the bottom 10 is fixed in the cylinder 1, but is provided with one or more perforations 12. Upon the bottom 10 a thin paper diaphragm is fixed at the edge 14 by adhesive means or other manner. The said diaphragm is also provided with one or more perforations 13, which perforations 13 are so arranged, that they never cover a perforation 12 e. g., that it must be impossible that, when the movable cylinder 1 is pressed over the inner cylinder, the compressed air will pass from the inner space between the surfaces 10 and 9 (Fig. 1) through the perforations 13 and 12 to the outside.

The cylinders may assume varied dimensions and forms and are made of cardboard, wood, tinned sheet iron, plastic or the like and the bag may be made of paper, rubber or other suitable material.

What I claim is:

1. A dust gun, which comprises: an outer cylindrical member of rigid material open at its top; an inner cylindrical member of rigid material open at its bottom, said inner cylindrical member being telescoped within said outer cylindrical member, and slidable with respect thereto; a check valve in the bottom end portion of said outer cylindrical member, said check valve permitting air to enter within said outer cylindrical member, but preventing air from escaping therefrom when said outer cylindrical member is slid with respect to said telescoping inner cylindrical member so that its bottom end approaches the open bottom portion of said inner cylindrical member; a perforated lid secured to said inner cylindrical member at its upper end portion; and a bag for powder positioned within said inner cylindrical member and fixed thereto in a substantially air-tight manner with only its upper

edge portion secured to the inside upper edge portion of said inner cylindrical member adjacent said perforated lid, said bag having air impervious side walls and bottom, the length of said bag along the cylindrical wall of said inner cylindrical member being less than the length of said inner cylinder wall, so that the bottom of said bag is above the bottom edge portion of said inner cylindrical member and the cross-sectional area of the bag, substantially throughout its length, being substantially equal to the cross-section of the inner cylindrical member.

2. A dust gun as defined in claim 1, wherein said check valve in the bottom end portion of said outer cylindrical member comprises a bottom plate which is tightly pressed against the wall of said outer cylindrical member in substantially air-tight engagement therewith when said bottom plate is subjected to air pressure from within

said outer cylindrical member, but which is released to permit air to enter within said outer cylindrical member when the pressure of air within said outer cylindrical member against said bottom plate is released.

ALBERT MORSINK.
